UNITED STATES PATENT OFFICE.

ANDREW J. BALDWIN, OF PIKEVILLE, KENTUCKY.

MINE-CAR COUPLING.

Application filed April 26, 1923. Serial No. 634,789.

To all whom it may concern:

Be it known that ANDREW J. BALDWIN, a citizen of the United States of America, residing at Pikeville, in the county of Pike 5 and State of Kentucky, has invented new and useful Improvements in Mine-Car Couplings, of which the following is a specification.

The object of the invention is to provide 10 a device of the kind abovementioned that will permit the coupling of mine cars irrespective of which end of the car faces the car to which it is to be coupled; to provide a coupling which will reduce to a minimum, 15 when in coupled position, the play or lost motion between cars which results in spilling coal at the sides of the track; to provide a coupling member having means insuring its alignment with the coupling member 20 with which it is to be engaged; to provide a coupling structure which will permit the coupling of cars on a curve or when the cars are disposed at a slight angle to each other such as is the case in mines where the tracks 25 are not always regular and straight; and to provide a coupling which may be readily disengaged when desired and which is insured maintaining its coupling relation irrespective of the vibration or bouncing of the cars 30 by which the members are carried.

With these general objects in view the invention consists in a certain construction and combination of parts of which a preferred embodiment is illustrated without defining 35 the limits of the invention.

In the accompanying drawings:

Figure 1 is a side elevational view of the adjacent extremities of two mine cars showing the application of the invention thereto 40 and in coupled position.

Figure 2 is a top plan view of the structure of Figure 1.

Figure 3 is a top plan view of the structure of Figure 1 but showing the cars disposed at an angle to illustrate the manner 45 in which the coupling members are aligned in such positions of the cars.

Figure 4 is a longitudinal sectional view on the line 4-4 of Figure 2.

Figure 5 is a perspective view of one of 50 the coupling members.

Figure 6 is a perspective view of the guide for the rear end of the spring by which the coupling member is retained in position longitudinally of the car.

Figure 7 is a perspective view of the bumper plate or member by which the coupling is shifted angularly as in coupling operations on curves.

The application of the invention necessitates the use in connection with a mine car 1 of an end sill 2 the forward edge of which is of arcuate contour in plan so as to provide an arcuate forward edge transversely of the car. This sill together with the draft bar constitutes the draft element by which the car is moved through a coupling member 3 which is mounted on the upper end of a pivot pin 4, the coupling member having a bifurcated rear end to provide spaced legs 5 disposed on opposite sides of the upper end of the pin 4 the head of which is square as indicated at 6 and a transverse pin 7 passing through the legs 5 and a head 6 and providing a pivotal mounting for the coupling so that the latter may swing in a vertical plane, the pin 7 being formed with a square or hexagonal head at one end and receiving at the other end a cotter pin 8 by which the pin is retained in position.

Disposed below the coupling member 3 is the bumper plate 9 which is cross sectionally angular or L-shaped, the vertical flange 9^a overhanging the front face of the sill 2 and the horizontal flange 9^b being triangular in plan and formed near the apex of the triangle with a square eye in which the square head 6 of the pin 4 seats. The pin 4 passes vertically through the sill 2 in an opening in which it is loosely mounted for pivotal movement in a horizontal plane. Thus the bumper plate may swing with the axis of the pin 4 as a center and because of the rounded forward edge of the sill 2 but any swinging or angular movement of the bumper plate is attained with a corresponding angular movement of the coupling member since there is a positive connection between the two, due to the head 6, so far as any relative angular movement in a horizontal plane is concerned. Therefore, if two cars being coupled are disposed on a curve or at an angle, as in Figure 3, their respective bumper plates will contact at the end and because of the pivotal mounting of the two will be moved gradually into parallelism and subsequent contact during which interval the coupling operation is effected, since each coupler at the free end is formed

with a tapered nose 10 and an intermediate neck portion 11 which define a rearwardly and laterally extending hook member 12. Since the coupling members at each end of 5 the car are alike they are oppositely disposed at opposite ends of the car and connecting coupling members have the noses 10 disposed in opposite relation as well as the hook members 12 and the inclined faces connecting the terminals of the noses with the 10 terminals of the hook members constitute camming surfaces by which relative running movement of the coupling members is effected in the coupling operation, until the hook 15 member of each engages in the throat defined by the neck and hook member of the other.

Obviously in the application of a draft to the coupling as in the movement of cars, 20 the coupling may swing laterally to accommodate curves in the track or irregularities in the same, the bumper plates moving with the coupling members. When it is desired to uncouple, it is only necessary to move the 25 cars to bring the bumper plates into contact when the looseness of engagement between the coupling members will be sufficient to permit either one being swung up to its pivotal connection with the pin 7 to disengage it from the other.

The coupling member is limited in pivotal movement downward to a horizontal position by contact with the upper flange 9^b of the bumper plate and the latter also 35 functions to prevent the disengagement of the couplings due to vibration of the connected ends of the cars, since the nose of each overlaps the bumper plate of the other and should the end of one car be subject 40 to an oscillation moving its end sill to a higher plane than that of the following car, it will engage the nose of the coupling member of the following car and raise that with it. Thus the coupling members are 45 insured of being held in engaged relation despite the usual oscillation of the cars due to irregularities in the track.

The invention also contemplates the use 50 of means to hold the coupling members normally longitudinally disposed of the cars to which they are attached and to this end a flat spring bar 14 is employed, its forward end being engaged in a slot formed in the lower end of the pin 4. The spring bar is 55 retained in engagement with the pin 4 by a transverse pin 15 extended transversely through the pin 4 and crossing the slot in the latter and pivotally engaging the spring bar, this pin 15 receiving cotter pins 16 by 60 which it is removably held in place. A take up collar or washer 17 is interposed between the spring bar and the lower face of the end sill 2. The spring bar is designed 65 to be held in a position longitudinally of the car and to this end a U-shaped guide 18

is provided, the arms of which are formed with slots slidably receiving the rear end of the spring bar and the web being pivotally connected with a button head bolt 19, the shank of which extends through the draw 70 bar 20 of the car and receives interior to the car a retaining nut 21. Obviously swinging movement imparted to the coupler by the rocking of the bumper plate will result in flexing the spring bar but the latter at 75 its rear end being slidably mounted in the guide 18 and the latter being pivoted to the bolt 19, this flexing results without the application of any tensile stress to the spring bar and the resiliency of the latter is always 80 available to return the coupling member to a position longitudinally of the car when the force tending to flex the spring bar is removed as in coupling operations on curves 85 and the like.

Having described the invention, what is claimed as new and useful is:—

1. A mine car coupling comprising a coupling member formed with a nose and with a hook element rearwardly of the nose, 90 a pivotal mounting for the coupling member to permit swinging movement in a horizontal plane, and a bumper plate connected with said pivotal mounting for pivotal movement corresponding with the coupling member, the bumper plate being disposed adjacent the hook element of the coupling member so that the nose of a connected coupling member may overlap the plate to preclude disengagement of the hook members of connected coupling members upon relative movement in a vertical plane of the connected ends of coupled cars. 95

2. A mine car coupling comprising in combination with a mine car having a sill, 105 a pivot pin carried by said sill and having angular or turning movement therein, a coupler secured to the upper end of said pin, a spring bar secured to the lower end of said pin and disposed longitudinally of the car, a guide carrying the remote end of said spring bar, and a bumper plate angular or L-shaped in cross section having one flange overhanging the forward edge of the sill and the other flange positively connected with said pin for pivotal movement 110 in a horizontal plane with the axis of the pin as a pivot.

3. A coupling consisting of complementary members of which each comprises a bumper plate pivotally mounted and yieldingly held in a position transverse to the car on which it is mounted, and a hooked coupling member mounted on the bumper plate and pivoted for movement in a plane perpendicular to said bumper plate, said hooked coupling member being limited in downward movement to a horizontal plane. 125

4. A coupling consisting of complementary members of which each comprises a bumper 130

plate pivotally mounted and yieldingly held in a position transverse to the car on which it is mounted, and a hooked coupling member mounted on the bumper plate and pivoted for movement in a plane perpendicular to said bumper plate, said hooked coupling member being limited in downward move-

ment to a horizontal plane, and having a nose portion overhanging the bumper plate of the complementary member when the hooks of the two are in coupling relation.

In testimony whereof he affixes his signature.

ANDREW J. BALDWIN.
